CLAIM

The ornamental design for a vocal trainer as shown and described.

DESCRIPTION

FIG. 1 is a front elevation view of the vocal trainer;
FIG. 2 is a rear elevation view thereof;
FIG. 3 is a left side elevation view thereof, the right side elevation view being a mirror image thereof;
FIG. 4 is a top plan view thereof;
FIG. 5 is a bottom plan view thereof;
FIG. 6 is a front left top perspective view thereof;
FIG. 7 is a rear left top perspective view thereof;
FIG. 8 is a front elevation exploded view of the vocal trainer;
FIG. 9 is a rear elevation exploded view thereof;
FIG. 10 is a left side elevation exploded view thereof, the right side elevation exploded view being a mirror image thereof;
FIG. 11 is a top plan exploded view thereof;
FIG. 12 is a bottom plan exploded view thereof;
FIG. 13 is a front left top perspective view of the body thereof;
FIG. 14 is a rear left top perspective view of the body thereof;
FIG. 15 is a rear bottom left perspective view of the slider thereof;
FIG. 16 is a front left top perspective view of the slider thereof; and,
FIG. 17 is an alternative front left top perspective view of the slider thereof.
